[57] **CLAIM**

The ornamental design for sport sox, substantially as shown and described.

DESCRIPTION

FIG. 1 is a top plan view of a sport sox showing my new design as looking into the opening of the sock;

FIG. 2 is a side elevational view thereof, the opposite side being a mirror image;

FIG. 3 is a front elevational view thereof;

FIG. 4 is a rear elevational view thereof;

FIG. 5 is a bottom plan view thereof;

FIG. 6 is a top plan view, similar to that of FIG. 1, illustrating a modification of my sport sox;

FIG. 7 is a side elevational view thereof, the opposite side being a mirror image;

FIG. 8 is a front elevational view thereof;

FIG. 9 is a rear elevational view thereof;

FIG. 10 is a bottom plan view thereof.
